METAL ROOFING

Joseph F. Zavodsky, Alva, Okla.

Application August 29, 1940, Serial No. 354,772

3 Claims. (Cl. 108—18)

This invention relates to an improved construction of metal roofing and more particularly to improved means for interlocking strips or sections of metal roofing and for covering the driven fastenings employed for securing the strips or sections to a roof surface to be covered by the roofing strips.

More particularly, it is an aim of the invention to provide a construction of metal roofing having interlocking joints for connecting the roofing sections or strips, said joints being so designed as to enclose and engage driven fastenings by means of which the sections or strips are attached to a surface to be covered.

Other objects and advantages of the invention will hereinafter become more fully apparent from the following description of the drawing, which illustrates preferred embodiments of the invention, and wherein:

Figure 1 is an end view showing a plurality of the roofing strips interlocked with one another and fastened to a surface to be covered thereby.

Figure 2 is a perspective view, on an enlarged scale, of one of the strips shown in Figure 1.

Figure 3 is an end view in elevation of another embodiment of the invention, and

Figure 4 is a similar view of still another embodiment of the invention.

Referring more particularly to the drawing, wherein like reference characters designate like or corresponding parts throughout the different views, 10 designates generally a strip of roofing material which is preferably formed of sheet metal and which may be of any desired length and width. One longitudinal edge of the strip 10 is rolled to form an upset tube like portion 11 which is open at its bottom 12. The strip 10 is also rolled adjacent its opposite longitudinal edge to form an upset tube like portion 13 which is likewise provided with a slotted opening 14 in the bottom thereof. The tube like portions 11 and 13 preferably extend the length of the strip 10. The tube like portion 13 is smaller than the tube like portion 11 and its slot 14 is smaller than the slotted opening 12. The longitudinal edge of the strip 10 which is disposed beyond or on the outer side of the tube like portion 13 forms a securing flange 15 which is provided with a plurality of spaced apertures 16 for receiving driven fastenings.

A plurality of the strips 10 are adapted to be mounted to cover a roof surface 17 and to form a sheet metal roofing. To apply the strips 10, one strip 10 is first laid in proper position on the surface 17 and secured thereto by means of

5 a number of driven fastenings 18 which extend through the openings 16. The tube like portion 11 of another strip 10 is then telescoped over the tube like portion 13 of the strip 10 which has already been secured. The last mentioned strip 10 projects from the side edge of the first mentioned strip 10 which is provided with the flange 15 so that its intermediate portion 19 overlies the flange 15 and the fastenings 18 of the first strip 10. The flange 15 of the last strip 10 is then attached by additional fastenings 18 to the surface 17. This operation is repeated with each additional strip 10 for interlocking the strips to form the metal roof and for securing the strips so that the fastenings 18 will all be covered.

Instead of the fastenings 18, the strips 10 may be secured by means of relatively large headed nails 20 which are first driven into the surface 17 sufficiently so that the heads 21 of the nails 20 will be elevated above the surface 17, as illustrated in Fig. 1. A strip 10 is then applied to the surface 17 and the tube like portion 13 thereof slid into position over the head 21 with the shank of the nail 20 extending through the slotted opening 14. Obviously, a number of nails 20 may be employed to engage each of the tube like portions 13. A second strip 10 is then slid in like manner over the heads 21 of additional nails 20 while at the same time the tube like portions 11 of the second strip 10 is telescoped over the tube like portion 13 of the first strip 10 for interlocking the two strips. This operation is likewise repeated until all of the strips 10 have been applied and connected to form the complete roof structure.

In lieu of the driven fastenings 18 or the nails 20 the strips 10 may be attached to the roof surface 17 by means of nails 22, as also illustrated in Figure 1, which are driven through the upper portion of the tube like portion 13 and which extend through the slotted opening 14. The heads of the nails 22 are made relatively flat and are forced down tight against the tube like portion 13 so that the tube like portion 11 of another strip 10 may be telescoped thereover for interlocking the two strips after which the portion 13 of the second strip is similarly fastened by nails 22. It will thus be seen that three ways of fastening the strips 10 by means of driven fastenings to the roof surface 17 are illustrated in Figure 1 and by each means the driven fastenings are covered to protect them from the elements to prevent rusting and also to prevent leakage through the openings through which

said fastenings extend to thereby form a roofing construction wherein no fastenings are exposed. As the tube like portion 11 of the first strip 10 which is laid may be disposed at an end of the surface 17 in which case it would not engage over a tube like portion 13, this portion 11 may engage heads 21 of nails 20, in the manner, as illustrated in Figure 1, to thereby secure the free end of the first strip 10 to the surface 17.

In Figure 3 another embodiment of the invention is disclosed wherein a modified form of roofing strip 23 is shown provided with three longitudinally disposed tube like portions 24 which correspond to the tube like portions 13 and which are provided with slotted openings 25 in their under sides. The side edges of the strip 23, which are disposed beyond the outer tube like portions 24, form flanges 26, corresponding to the flanges 15 and which are adapted to be fastened to the roof surface 17 by fastenings 18. The intermediate tube like portion 24 is held in place by means of a number of nails 20, in the same manner, as illustrated in Figure 1. A portion of a second roofing strip 23a is shown in Figure 3 which is provided along each of its longitudinal edges with a tube like portion 27, one of which portions 27 is shown in Figure 3. The strips 23 and 23a are arranged alternately with the strips 23 first being attached to the roof surface 17 after which the tube like portion 27 of each longitudinal edge of a strip 23a is telescoped over the portions 24 which are disposed adjacent to adjacent edges of two spaced roofing strips 23 to thereby interlock the strip 23a simultaneously with two strips 23. This operation is repeated until the complete roof is formed.

In Figure 4, a third embodiment of the invention is disclosed including roofing strips 28, each of which is provided along one longitudinal edge with a tube like portion 29 corresponding to the portion 11 of the strip 10. The strips 28 are provided with flanges 30 formed by their opposite longitudinal edges. Adjacent the flanges 30, each of the strips 28 is folded twice upon itself to form an upwardly projecting interlocking portion 31 which is V-shaped in cross section. To apply strips 28 to the roof surface 17 tube like portion 29 of the first strip 28 is slid over headed nails 20 for attaching the edge of the strip 28 thereof which is formed by the portion 29 to the surface 17. The flange 30 of said strip 28 is then secured by means of driven fastenings 18 to the surface 17. The tube like portion 29 of a second strip 28 is then telescoped over the portion 31 of the first strip 28 after which the flange 30 of the second strip 28 is secured by fastenings 18 to the surface 17. This operation is repeated for interlocking the different strips 28 and for securing them to the surface 17 until the roofing is completed.

It will be noted that in each of the three embodiments of the invention all driven fastenings which are used are covered. On extreme flat

roofs, all of the joints formed, in each of the three embodiments of the invention, can be sealed with paint or plastic material to insure against leakage. The different embodiments of the invention may be employed with either smooth or corrugated patterns of roofing and will provide a leakproof metal roof which will be rigid and which will require less roof support and produce a neat appearance.

Various modifications and changes are contemplated and may obviously be resorted to provided they fall within the spirit and scope of the invention as hereinafter defined by the appended claims.

I claim as my invention:

1. A metal roofing comprising elongated metal strips, each of said strips being provided with a plurality of rolled portions extending lengthwise thereof and forming upset tube like portions, said tube like portions having slotted openings in their under sides, one of said tube like portions being disposed adjacent each of the longitudinal edges of the strip, the tube like portion along one of the longitudinal edges of the strip being larger than the other of said tube like portions, said smaller tube like portion being constructed and arranged to receive the larger tube like portion of another corresponding strip for connecting the strips, and a headed driven fastening secured in a surface to be covered by the strip, the head of said driven fastening being disposed in the smaller of said tube like portions.

2. A metal roofing comprising a plurality of sheet metal roofing strips, each of said strips including a plurality of longitudinally disposed upset tube like portions, said tube like portions being open at their bottoms, certain of the tube like portions of the different strips being larger than other of the tube like portions, said smaller tube like portions telescoping into the larger tube like portions for interlocking the strips, and fastening means engaging a surface to be covered by said strips and having enlarged heads spaced from said surface for slidably engaging in the smaller of said tube like portions for retaining the strips in engagement with said surface.

3. A metal roofing comprising a plurality of sheet metal roofing strips, each of said strips including a plurality of longitudinally disposed upset tube like portions, said tube like portions being open at their bottoms, certain of the tube like portions of the different strips being larger than other of the tube like portions, said smaller tube like portions telescoping into the larger tube like portions for interlocking the strips, and headed driven fastenings disposed in a surface to be covered by the strips with the heads of the fastenings disposed in an elevated position relatively thereto for engaging the smaller of the tube like portions for attaching the strips to said surface in such a manner that the fastenings do not penetrate any of the strips.

JOSEPH F. ZAVODSKY.
